(57) **CLAIM**

The ornamental design for a cover for a spray gun, as shown and described.

DESCRIPTION

FIG. 1 is a top, left side, rear perspective view of a cover for a spray gun showing our new design in an environment of use with a spray gun;

FIG. 2 is a bottom, right side, front perspective view thereof; FIG. 3 is a rear perspective view of the cover for a spray gun of FIG. 1;

FIG. 4 is a front view thereof;

FIG. 5 is a left side view thereof;

FIG. 6 is a rear view thereof;

FIG. 7 is a top view thereof; and,

FIG. 8 is a bottom view thereof.

Broken lines illustrate environmental subject matter that forms no part of the claimed design.
